(57) **CLAIM**

We claim, the ornamental design for a golf shoe, as shown and described.

DESCRIPTION

FIG. 1 is a perspective view of a golf shoe, showing our new design;

FIG. 2 is another perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front view thereof; and,

FIG. 8 is a rear view thereof.

The broken lines in the figures show portions of the golf shoe that form no part of the claimed design.

1 Claim, 8 Drawing Sheets
